UNITED STATES PATENT OFFICE.

PAUL P. BANHOLZER, OF PHILADELPHIA, PENNSYLVANIA.

MECHANICAL SOUNDER FOR TELEGRAPH SYSTEMS.

1,163,201.

Specification of Letters Patent.

Patented Dec. 7, 1915.

Application filed April 3, 1912. Serial No. 688,228.

To all whom it may concern:

Be it known that I, PAUL P. BANHOLZER, a citizen of the United States, and a resident of Philadelphia, county of Philadelphia, 5 and State of Pennsylvania, have invented certain new and useful Improvements in Mechanical Sounders for Telegraph Systems, of which the following is a specification.

10 My invention relates to that class of devices wherein it is desired to transmit space signals over telephone lines, and my objects are: First, to provide a simple and efficient mechanism that may be removably attached to telephone instruments; second, to provide efficient means for transmitting mechanical sounds to telephone transmitters; third, to provide means for obtaining maximum amplitude of transmission of 15 mechanical sounds on operation of the sounder; fourth, to eliminate damping effects in the transmission of mechanical sounds to the telephone transmitter.

With these objects in view, my invention 20 consists of certain novel features of construction and arrangement of parts as will hereinafter be more fully described and pointed out in the claims, reference being had to the accompanying drawing forming 25 part of this specification and in which—

Figure 1 is a longitudinal section on A—B Fig. 2 and showing more particularly the arrangement of the sounding mechanism and the method employed for the mechanical 30 transmission of the sound vibrations to the ordinary telephone transmitter, Fig. 2 a plan of the sounder and showing the removable attached mechanism to the transmitter support.

35 Referring to the figures in which similar numerals of reference refer to similar parts throughout the several views, the numeral 1 designates the support and numeral 2 designates the transmitter of the ordinary telephone; 3 designates the sounder base on which the lever arm for the mechanical operation of sounder is mounted; the base 3 has an extended portion 17, more particularly shown in Fig. 2 and which is rounded 40 out to fit one half of periphery of the transmitter support 1; 19 designates a part similar to the extended portion 17 and which is also rounded out to fit the remaining periphery of the transmitter support 1; 4 designates screws which are in threaded en-

gagement with part 19; the part 17 is provided with holes 20 slightly larger than the diameter of the screws 4. It will be evident that upon the insertion of the screws 4 through the holes 20, that upon the threaded engagement of the screws 4 and the part 19 that the sounder base 3 can be rigidly clamped to the transmitter support 1. The base 3 is also provided with a substantially U-shaped bracket 7 and in which the sounder lever 5 is pivotally supported by means of a pin 6.

8 designates an operating knob in fixed relation with sounder lever 5. Base 3 is provided with a raised portion 9 and an extended portion or arm 10 limiting the angular travel of sounder lever 5 about its pivotal support pin 6.

11 designates a set screw provided with a lock nut 12 and is in threaded engagement with the extended portion 10. It will be evident that an adjustment of the angular travel of the sounder lever 5 about its pivotal support pin 6 can be effected by an adjustment of the set screw 11.

16 designates a lug extended from the base 3 and is provided with a hollow chamber 18, in which is inserted a compression spring 15.

13 designates a set screw provided with a lock nut 14 and which is in threaded engagement with the sounder lever 5. The end of the set screw 13 is rigidly connected to one end of the compression spring 15. It will be evident that spring 15 when under compression will tend to angularly revolve sounder lever 5 about its pivotal support pin 6 until it engages the end of the set screw 11. It will be further evident that the adjustment of the compression spring 15 can be effected by an adjustment of the set screw 13.

Having thus described the various parts throughout the several views all of which will be readily understood by those skilled in the art to which this invention relates, its operation will be substantially as follows: The sounder base 3 through its extended portion 17 and part 19 being in fixed relation to the transmitter support 1, it will be evident that upon the striking of the knob 8 the sounder lever 5 will engage the raised portion 9 and set up vibration which will be transmitted mechanically to the transmitter 105 110 115 120 125 130 135 140 145 150 155 160 165 170 175 180 185 ther evident that the sounder lever 5 will rotate about its pivotal support pin 6 and engage the set screw 11, due to the spring 15 being previously placed under compression.

5 It will be further evident that upon the engagement of the sounder lever 5 and set screw 11 that mechanical vibrations will be set up in sounder base 3 and transmitted to transmitter 2 as previously explained. The 10 signals mechanically transmitted to the transmitter 2 can be distinctly heard in a telephone receiver when using the line for telephone purposes. It will be further evident that Morse or other similar telegraph 15 signals may be transmitted to the telephone transmitter upon the operation of the knob 8 and the engagement of the sounder lever 5 and the raised portion 9 and the set screw 11.

20 By arranging the depth of the extended portion 17 and 19 so that the peripheral clamping area is considerable it has been found in practice that the mechanical transmission of sound to the telephone transmitter is greatly increased over what can be effected by mounting the sounder direct on the telephone support base; and thereby accomplishing the heretofore mentioned first 25 object of my said invention. It will be further evident that by pivoting the sounder lever at the extremity of base 3 that a maximum amplitude of sound vibrations is effected than could otherwise be obtained by pivoting the sounder lever intermediate 30 of the striking knob and the back stroke striking member such as is found in the ordinary telegraph key; and thereby accomplishing the heretofore mentioned second object of my said invention. It will be further evident that by arranging the sounder base 3 integral with the extended clamping portion 17 without any intervening secured fixed members that the damping effect of the transmission of mechanical sounds to 40 the telephone support is limited to a minimum; and thereby accomplishing the heretofore mentioned third object of my said invention. It will also be further evident that by the arrangement of the extended portion 17 and part 19 and the threaded engagement of member 4 and part 19 that a simple and effective device has been devised and which can be adjustably removably attached to a telephone instrument; 45 and thereby accomplishing the heretofore 50 55

ment and fourth object of my said invention.

I do not wish to limit myself to the exact construction of the apparatus as shown as it is evident that departures can be made therefrom without departing from the spirit and intent of my said invention, but—

What I claim as new and desire to secure by Letters Patent is:—

1. A mechanical signaling device comprising in combination with a telephone transmitter having a rigid metallic support, a mechanical sounder including a base rigidly and detachably clamped to the said support and having an abutment and a bracket 70 formed at opposite ends thereof, an arm integral with said base and arranged to project over and above the abutment thereon, and a spring-retracted sounding lever pivotally mounted in the bracket on the base 75 and adapted to engage the said abutment to set up vibrations for transmission to the said transmitter.

2. A mechanical signaling device comprising in combination with a telephone transmitter having a rigid metallic support, a base having a separable clamp for attaching the same to said telephone transmitter support; a substantially U-shaped bracket formed at one end of said base, an abutment 80 on the base opposite the bracket, an arm integral with said base and arranged to project over and above the abutment thereon, and a spring retracted sounding lever pivotally mounted on the bracket on the base 85 and adapted to engage the said abutment to set up vibrations for transmission to the said transmitter.

3. A mechanical signaling attachment for transmitter standards, comprising in combination with the standard, a rigid base carrying therewith clamping means for detachably and rigidly engaging the said standard and a bracket, a spring-pressed sounding lever directly pivoted to the said bracket, a contact element also carried by the base and 95 metallically engaged by the lever, and means carried by said base for limiting the play of said sounding lever.

In testimony whereof I have hereunto signed my name to this specification in the 105 presence of two subscribing witnesses.

PAUL P. BANHOLZER.
